UNITED STATES PATENT OFFICE.

LEOPOLD THOMAS, OF NEW YORK, N. Y.

GARBAGE-BAG.

No. 893,759.

Specification of Letters Patent.

Patented July 21, 1908.

Application filed November 28, 1906. Serial No. 345,497.

To all whom it may concern:

Be it known that I, LEOPOLD THOMAS, a citizen of the United States, residing at New York, in the county of New York and State 5 of New York, have invented a new and useful Garbage-Bag, of which the following is a specification.

This invention relates to garbage bags or receptacles and has for its object to provide 10 an inexpensive, durable and sanitary device of this character especially designed for use in apartment houses, private dwellings and similar places and adapted to be removed by the garbage collector and destroyed together 15 with the contents of the same.

A further object is to provide a water- 20 proof bag or receptacle having its side and bottom walls reinforced and its upper end provided with a draw-string whereby the mouth 25 of the bag may be closed so as to prevent escape of foul odors.

A still further object of the invention is to generally improve this class of devices so as to increase their efficiency and utility as well as 25 to reduce the cost of manufacture.

With these and other objects in view the invention consists in the construction and novel combination and arrangement of parts hereinafter fully described, and illustrated in 30 the accompanying drawings, it being understood that various changes in form, proportions and minor details of construction may be resorted to within the scope of the appended claims.

35 In the accompanying drawings forming a part of this specification: Figure 1 is a perspective view of a garbage bag or receptacle constructed in accordance with my invention. Fig. 2 is a longitudinal sectional view 40 of the same. Fig. 3 is a perspective view partly in section illustrating a modified form of bag or receptacle. Fig. 4 is a similar view illustrating a further modification.

Similar numerals of reference indicate 45 corresponding parts in all of the figures of the drawings.

The improved bag or receptacle comprises a body portion preferably formed of a single strip of paper, fabric or other suitable material the adjacent longitudinal edges of which are over-lapped and pasted or otherwise secured together to form a lap-seam 5, said body portion being provided with an extension or flap 6 adapted to be folded laterally 50 in engagement with the side walls 7 of the

body portion and which constitutes the bottom of the receptacle, as shown.

The interior walls of the receptacle are coated or otherwise covered with a water- 60 proof compound 8 thereby to render the bag impervious to moisture or if desired said receptacle may be formed of water-proof material.

Arranged within the outer receptacle is an 65 inner or reinforcing receptacle 9 which preferably extends approximately one-half the height of the side walls of the outer receptacle and serves to reinforce and strengthen said receptacle and prevent the escape of liquid.

The inner receptacle 9 may be formed of 70 thin metal but is preferably constructed of a single piece of water-proof paper, fiber, veneer or similar material the entire surface of which is glued, pasted or otherwise fastened to the adjacent inner surface of the 75 outer bag and made water tight. The adjacent longitudinal edges of the inner receptacle are over-lapped and secured to the interior walls of the outer receptacle at a point diametrically opposite the lap-seam 5, 80 as indicated at 10, but if desired said inner receptacle may be pressed or otherwise formed from a single sheet of tin foil or similar material thus dispensing with the lap-seam. By having the lap-seams of the inner and outer 85 receptacle arranged on opposite sides of the bag or body portion the liquid or semi-liquid material contained in the garbage is effectively prevented from working its way through the lap-seams and escaping from the 90 receptacle. The side walls of the outer receptacle are preferably provided with a plurality of openings or perforations 10 100 spaced inwardly from the mouth 11 of the receptacle and through which is threaded the 95 draw-string 12 whereby the mouth of the receptacle may be readily closed so as to prevent the escape of foul odors.

In using the device the receptacle is filled or partly filled with garbage and the string 100 12 drawn tight so as to contract the mouth of the receptacle and thus form a closure for the same. The receptacle is then placed in a convenient position for removal by the garbage-collector, said receptacle together 105 with the garbage being carried to the crematory and destroyed in the usual manner.

In Fig. 3 of the drawings there is illustrated a modified form of the invention in which the bag is rectangular in shape with 110

the adjacent ends of the paper or other material forming the bottom of the outer receptacle 7' over-lapped at 13 and glued or otherwise secured to the inner receptacle 9'.

5. The bag or receptacle shown in Fig. 4 is similar in construction to that shown in Fig. 3 only the side walls of the former are cylindrical and the bottom thereof circular in shape, as shown.

10. The receptacle may be made in different sizes and shapes and formed of paper, cloth, vegetable fiber or other suitable material.

15. From the foregoing description it will be seen that there is provided an extremely simple, inexpensive and efficient device admirably adapted for the attainment of the ends in view.

Having thus described the invention what is claimed is:

20. A device of the class described comprising an elongated flexible outer receptacle formed of a single piece of material the adjacent longitudinal edges of which are over-lapped and united to form a lap seam and one end 25 thereof provided with a flap adapted to be folded upwardly at right angles to the lap seam and fastened to the exterior walls of the outer receptacle, said flap extending the en-

tire width of the outer receptacle and constituting the bottom of the latter, there being 30 perforations formed in the side walls of the outer receptacle and spaced inwardly from the mouth thereof, one of the perforations piercing the over-lapped edges of the outer receptacle, a flexible water proof inner 35 receptacle permanently secured to the bottom and interior walls of the outer receptacle and having its adjacent longitudinal edges over-lapped to form a lap seam arranged diametrically opposite the lap seam of the outer 40 receptacle, said inner receptacle being smaller than the outer receptacle and of approximately one-half the height of the outer receptacle, and a draw string threaded through the perforations in the outer receptacle and 45 engaging alternately the interior and exterior walls of said outer receptacle for normally closing the mouth thereof.

In testimony that I claim the foregoing as my own, I have hereto affixed my signature 50 in the presence of two witnesses.

LEOPOLD THOMAS.
